UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed June 14, 1924. Serial No. 719,952

My present invention relates to water tube boilers particularly of the horizontally inclined water tube type, and will be best understood from the following description and 5 the annexed drawing showing a vertical sectional elevation of a steam boiler embodying my invention.

Over a furnace chamber 10 provided with a forced-blast underfeed stoker 11, a set of 10 horizontally inclined water tubes is arranged in three banks, the upper bank 12 having the greater number of rows of tubes, the middle bank 13 a lesser number, and the lower bank 14 two rows in the illustrative embodiment. 15 Each of the banks is separated from the adjacent bank by a wide space which preferably is made sufficiently large to permit a workman to enter the space to have access to the tubes, the superheater and the like, such 20 access openings being shown at 15 and 16.

The main upper bank 12 of the water tubes is connected to uptake headers or water chambers 17 and downtake headers or water chambers 18, these water chambers, in turn, being 25 connected in the usual manner to a steam and water drum 19.

Supplemental uptake water chambers 20 are connected by nipples 21 to the uptake water chambers 17 and supplemental downtake water chambers 22 are connected to the water chambers 18 by nipples 23.

Above the upper tubes of the bank 14 is a 30 roof baffle 24 extending from the water chambers 22 toward the chambers 20 and from the inner end of the baffle 24, preferably at an 35 inclination to the vertical, is a baffle extending across the middle bank 13 and upper bank 12. Preferably this baffle is made up of two parts, the lower part 25 extending 40 across the middle bank 13 and the upper part 25^a across the upper bank 12. A second baffle 26 extends downwardly across the upper bank 12 and by an extension 26' across the space between the upper bank 12 and the middle bank 13.

In the arrangement illustrated, I have provided a superheater having U-tubes 27 extending in the same direction as the water tubes of the boiler and located in the first 50 gas pass of the boiler in the space between the upper and middle banks with an inlet header 28 and an outlet header 29 connected to the tubes and located in the second gas pass of the boiler. The headers 28 and 29 are suspended by supports 30 attached to the water

tubes of the upper bank, the tubes 27 being supported at their outer ends by the supports 32 connected to the water tubes of the upper bank and a line of bricks or tile 32^a resting on the tubes 13. The intake header 60 28 receives its steam from the drum 19 through the pipe 33.

Preferably the lower part 25 of the first cross baffle will be positioned out of alignment with the upper part 25^a and nearer the uptake water chambers, to provide a wider pass between the lower part 25 and the bottom of baffle 26' than would be provided if the parts 25 and 25^a were in alignment, the lower part 25, however, being preferably 70 spaced far enough from the uptake water chambers so that the pass into the bottom of the superheater chamber is at least as wide as the entrance into the first pass across the upper bank 12. The upper part 25^a and the 75 lower part 25 are connected by a suitable baffle 25^b, of which the superheater boxes form a part.

In the arrangement described, the gases 80 from the furnace 10 first pass over the tubes in the bank 14 which are exposed for substantially their full length to the furnace, and then through the pass defined by the baffle 25 upwardly across the three banks, and thence 85 downward over the main bank and also over the second bank and back again to the gas outlet 34.

By placing the baffle 24 relatively close to the furnace, the furnace temperature is increased, since the direct heat absorption 90 from the furnace is reduced to a few tubes only instead of a large number, as would be the case if the baffle 24 were located above the tubes defining the superheater chamber. At the same time, by continuing the baffle 26, 95 26' downward across the space provided for the superheater chamber, contact of the gases with the lower portions of the tubes of the middle bank with the gases is insured, whereby the efficiency of the boiler is increased. 100

By inclining the baffle 25^a to the vertical, a gas pass which is restricted above the superheater, is provided, and, at the same time, one in which the possible accumulation of dust and slag thereon will be minimized. 105

By making the spaces between the banks of large size, access to such spaces may be readily obtained.

Again, by employing two lines of tubes for the lower bank 14 with a wide space between 110

the lower bank and the middle bank 13, the tubes of the lower bank which come beneath the first pass serve as an effective slag screen. If desired, the tubes of the lower bank may 5 be arranged as shown in any other form to make an effective slag screen, such as shown in the copending applications of Howard J. Kerr, Serial No. 683,127, filed December 28, 1923 or Isaac Harter, Serial No. 594,201, renewed December 31, 1923, Patent No. 10 1,568,555.

Soot blowers 34 are installed above the tubes of the lower bank in the positions indicated, for removing slag from the tubes, 15 these soot blowers being protected by means of cast-iron shields as described in my copending application Serial No. 417,194, filed October 15, 1920.

It will be understood that the arrangement 20 which I have shown is merely illustrative and that its embodiment may be widely varied.

I claim:

1. A boiler having horizontally extending 25 water tubes connected at their ends to uptake and downtake water chambers, said tubes being divided to form a lower, a middle and an upper bank with a space between each pair of successive banks, a roof baffle extending from 30 the downtake water chamber along the tubes of the lower bank, a first cross baffle extending upwardly from the inner end of said roof baffle across tubes of the middle and upper banks, a second cross baffle extending down- 35 wardly across the upper bank and entering the space between the upper and middle banks and a superheater located in the first pass between the uptake water chamber and said first cross baffle and in the space between the upper 40 and the middle banks and with substantially all of its tube heating surface located in the first pass.

2. A boiler having horizontally extending 45 water tubes connected at their ends to uptake and downtake water chambers, said tubes being divided to form a lower, a middle and an upper bank with a space between each pair of successive banks, a roof baffle inclined to the horizontal towards the uptake water 50 chamber and extending from the downtake water chamber along the tubes of the lower bank, a first cross baffle extending upwardly from the inner end of said roof baffle across the tubes of the middle and upper banks and 55 towards said uptake chambers, a second cross baffle extending downwardly across the upper bank and entering the space between the upper and middle banks, and a superheater in the first pass between the uptake water chamber and said first cross baffle and in the space between the upper and middle banks.

3. A boiler having horizontally extending 60 water tubes connected at their ends to uptake and downtake water chambers, said tubes being divided to form a lower, a middle and an

upper bank with a space between each pair of successive banks, a roof baffle extending from the downtake water chamber along the tubes of the lower bank, a first cross baffle extending upwardly from the inner end of said roof baffle across the tubes of the middle and upper banks and towards said uptake chambers, a second cross baffle extending downwardly across the upper bank and entering the space between the upper and middle banks, and a 70 superheater in the first pass between the uptake water chamber and said first cross baffle and in the space between the upper and the middle banks, said superheater having tubes 75 extending in the same direction as the water tubes and through said first cross baffle, with boxes in the second gas pass of the boiler.

4. A boiler having horizontally extending 80 water tubes connected at their ends to uptake and downtake water chambers, said tubes being divided to form a lower, a middle and an upper bank with a space between each pair of successive banks, a roof baffle extending from the downtake water chamber along the tubes of the lower bank, a first cross baffle 85 extending upwardly from the inner end of said roof baffle across the tubes of the middle and upper banks, a second cross baffle extending downwardly across the upper bank and entering the space between the upper and middle banks, and a superheater in the first 90 pass between the uptake water chamber and said first cross baffle and in the space between the upper and the middle banks, said superheater having tubes extending in the same direction as the water tubes and through said first cross baffle, with boxes in the second gas pass of the boiler, said boxes being supported 95 from the water tubes of the upper bank.

5. A boiler having horizontally extending 100 water tubes connected at their ends to uptake and downtake water chambers, said tubes being divided to form a lower, a middle and an upper bank with a space between each pair of successive banks, a roof baffle inclined to the horizontal towards the uptake water chamber and extending from the downtake water chamber along the tubes of the lower bank, a first cross baffle extending upwardly 105 at an inclination to said chambers from the inner end of said baffle across the tubes of the middle and upper banks, a second cross baffle extending downwardly across the upper bank and entering the space between the upper and middle banks, and a superheater in the 110 first pass between the uptake water chamber and said first cross baffle and in the space between the upper and the middle banks, said superheater having tubes extending in the same direction as the water tubes and through 115 said first cross baffle, with boxes in the second gas pass of the boiler.

6. A boiler having horizontally extending 120 water tubes connected at their ends to uptake and downtake water chambers, said tubes be- 125

ing divided to form a lower, a middle and an upper bank with a space between each pair of successive banks, a roof baffle extending from the downtake water chamber along the

5 tubes of the lower bank, a cross baffle extending upwardly from the inner end of said roof baffle and towards said uptake chambers across tubes of the middle and upper banks, and a superheater in the space between the

10 middle and upper banks.

7. A boiler having horizontally extending water tubes connected at their ends to uptake and downtake water chambers, said tubes being divided to form a lower, a middle

15 and an upper bank with a space between each pair of successive banks, a roof baffle extending from the downtake water chamber along the tubes of the lower bank, a cross baffle inclined to the vertical extending upwardly

20 from the inner end of said roof baffle across tubes of the middle and upper banks to cause the gases to flow through a pass of progressively decreasing width in their first pass over the boiler tubes, said cross baffle being in two

25 parts, the lower part extending across the middle bank and the upper part extending across the upper bank, said parts being approximately parallel and out of alinement, with the space between the top of said lower

30 part and the adjacent water chamber at least as great as the space between the bottom of said upper part and the adjacent water chamber.

8. A boiler having horizontally extending water tubes connected at their ends to uptake and downtake water chambers, said tubes being divided to form a lower, a middle and an upper bank with a space between each pair of successive banks, a roof baffle extending from

35 the downtake water chamber along the tubes of the lower bank, a cross baffle inclined to the vertical extending upwardly from the inner end of said roof baffle across tubes of the middle and upper banks to cause the gases to flow

40 through a pass of progressively decreasing width in their first pass over the boiler tubes, said cross baffle being in two parts, the lower part extending across the middle bank and the upper part extending across the upper bank, said parts being approximately parallel

45 and out of alinement, with the space between the top of said lower part and the adjacent water chamber at least as great as the space between the bottom of said upper part and the adjacent water chamber, and said lower part

50 being positioned between the adjacent water chamber and the plane of said upper part.

9. A boiler having horizontally extending water tubes connected at their ends to uptake and downtake water chambers, said tubes being divided to form a lower, a middle and an upper bank with a space between each pair of successive banks, a roof baffle extending from the downtake water chamber along the tubes

55 of the lower bank, a cross baffle inclined to

the vertical and towards said uptake chambers extending upwardly from the inner end of said roof baffle across tubes of the middle and upper banks to cause the gases to flow through a pass of progressively decreasing width in 70 their first pass over the boiler tubes, and a superheater in the space between the middle and upper banks.

10. A boiler having horizontally extending water tubes connected at their ends to uptake and downtake water chambers, said tubes being divided to form a lower, a middle and

an upper bank with a space between each adjacent pair of banks, a roof baffle extending from the downtake water chamber along the 80

tubes of the lower bank, a first cross baffle inclined to the vertical extending upwardly from the inner end of said roof baffle across tubes of the middle and upper banks, a second

cross baffle extending downwardly across the upper bank and entering the space between the upper and middle banks, a superheater in the first pass between the uptake water chamber and said first cross baffle and in the

85 space between the upper and middle banks, said first cross baffle being in two parts with the lower part extending across the tubes of the middle bank nearer the uptake water chamber than it would be if in line with the upper part extending across the upper bank. 90

11. A boiler having horizontally extending water tubes connected at their ends to uptake and downtake water chambers, said tubes being divided to form a lower, a middle and

an upper bank with a space between each adjacent pair of banks, a roof baffle extending from the downtake water chamber along the tubes of the lower bank, a first cross baffle inclined to the vertical extending upwardly

100 from the inner end of said roof baffle across tubes of the middle and upper banks, a second cross baffle extending downwardly across the upper bank and entering the space between the upper and middle banks, a superheater in the first pass between the uptake water

105 chamber and said first cross baffle and in the space between the upper and middle banks, said first cross baffle being in two parts with the lower part extending across the tubes of the middle bank nearer the uptake water

110 chamber than it would be if in line with the upper part extending across the upper bank, the top of said lower part being spaced from the uptake water chambers a distance at least

115 as great as the distance between the bottom of said upper part and the uptake water chambers.

12. A boiler having horizontally extending water tubes connected at their ends to uptake and downtake water chambers, said tubes being divided to form a lower, a middle and

120 an upper bank with a space between each adjacent pair of banks, a roof baffle extending from the downtake water chamber along the tubes of the lower bank, a first cross

125

- baffle inclined to the vertical extending upwardly from the inner end of said roof baffle across the tubes of the middle and upper banks, a second cross baffle extending downwardly across the upper bank and entering the space between the upper and middle banks, a superheater in the first pass between the uptake water chamber and said first cross baffle and in the space between the upper and middle banks, said first cross baffle being in two parts with the lower part extending across the tubes of the middle bank nearer the uptake water chamber than it would be if in line with the upper part extending across the upper bank, the top of said lower part being spaced from the uptake water chambers a distance at least as great as the distance between the bottom of said upper part and the uptake water chambers, and the space between said lower part and the bottom of said second cross baffle being at least as great as the space between the bottom of said second cross baffle and the downtake water chambers.
13. A boiler having horizontally extending water tubes connected at their ends to uptake and downtake water chambers, said tubes being divided to form a lower, a middle and an upper bank with a space between each pair of successive banks, a roof baffle extending from the downtake water chamber along the tubes of the lower bank, a cross baffle inclined to the vertical and towards said uptake chambers extending upwardly from the inner end of said roof baffle across tubes of the middle and upper banks, and a superheater in the space between the middle and the upper banks, the lower bank being widely spaced from the middle bank and the number of tubes in the lower bank being relatively few, whereby a slag screen for the tubes of the middle bank is formed.
14. A boiler having horizontally extending water tubes connected at their ends to uptake
- and downtake water chambers, said tubes being divided to form a lower, a middle and an upper bank with a space between each pair of successive banks, a roof baffle extending from the downtake water chamber along the tubes of the lower bank, a first cross baffle extending upwardly from the inner end of said roof baffle across tubes of the middle and upper banks, a second cross baffle extending downwardly across the upper bank, and a superheater located in the first pass between the uptake water chamber and said first cross baffle and in the space between the upper and the middle banks and with its tube heating surface located solely in the first pass.
15. A boiler having horizontally extending water tubes connected at their ends to uptake and downtake water chambers, said tubes being divided to form a lower, a middle and an upper bank with a space between each pair of successive banks, a roof baffle extending from the downtake water chamber along the tubes of the lower bank, a first cross baffle inclined to the vertical and towards said uptake chambers extending upwardly from the inner end of said roof baffle across tubes of the middle and upper banks, a second cross baffle extending downwardly across the upper bank, a superheater in the first pass between the uptake water chamber and said first cross baffle and in the space between the upper and middle banks, said first cross baffle being in two parts with the lower part extending across the tubes of the middle bank nearer the uptake water chamber than it would be if in line with the upper part extending across the upper bank, the top of said lower part being spaced from the uptake water chambers a distance at least as great as the distance between the bottom of said upper part and the uptake water chambers.
